UNITED STATES PATENT OFFICE

SPENSER FLOWER, OF SHIPSTON-ON-STOUR, ENGLAND

PRESS FOR RACKETS

Application filed March 1, 1928, Serial No. 258,336, and in Great Britain December 15, 1927.

This invention relates to presses for rackets, and its primary object is to improve the construction and facilitate the operation thereof and at the same time dispense with the usual nuts and screws by which the required pressure is obtained. The improved construction of press also enables it to be packed or stowed away in less space than hitherto, and also facilitates the introduction and removal of the rackets.

According to the invention movable means are provided with a part capable of moving the upper and lower frames of the press towards each other when the means are moved in one direction and of permitting the frames to be moved away from each other when the means are moved in the opposite direction. The upper and lower frames of the press are preferably pressed onto the racket or released from the same for clamping or unclamping the racket therein, by one or more cranks, eccentrics, cams or equivalent parts (hereinafter referred to as cranks), operated by the means connected therewith. Each of the said cranks may be individually actuated by a lever or equivalent movable member, or two or more of such cranks may be adapted to be operated collectively by a single lever or equivalent movable member. In the latter form where one lever or equivalent movable member is adapted to operate two or more of the said cranks, the latter are operated simultaneously thereby and one movement thereof suffices to clamp or unclamp a racket in the press. The one or more cranks may be arranged to operate on the said frames through the medium of one or more plates or similar attachments provided in connection with the said frames. The plates or similar parts may be of a resilient or spring construction or form parts of springs, and serve to compensate for any slight wear of the said cranks to equalize the pressure exerted through the frames, and to allow for any variations in the thickness of the rackets. The upper and lower frames may be held spaced from each other by spacing devices such as springs or collars. The one or more movable levers or members or the

cranks are connected to projections or parts on one frame and adapted to co-act with the other frame or parts connected therewith for clamping or unclamping purposes. The frames may be of open or closed construction and when of closed form may be provided with extensions for wholly enclosing the racket in the press and preventing damage to the gut stringing. The latter may be partially protected by closed forms of frames without the extensions.

In order that the said invention may be clearly understood and readily carried into effect, the same will now be more fully described by way of example with reference to the accompanying drawings, in which:

Figure 1 is a plan view of one construction of the racket press showing part of a tennis racket in position therein.

Figures 2 and 3 are transverse sections respectively taken on the lines 2-2 and 3-3 of Figure 1.

Figure 4 is a transverse section taken on the line 4-4 of Figure 1, and showing the crank or cam ends of the movable member in two different positions.

Figures 5 and 6 are respectively a plan view and a section taken on the line 6-6 of Figure 5, illustrating an alternative construction of the racket press.

Figures 7 and 8 are sections of part of the press illustrating modifications herein-after described.

Referring to the racket press shown in Figures 1 to 4 inclusive, this comprises an upper frame *a* and a lower frame *b*. Each frame is constituted by bars of channel shape in cross section as more particularly shown in Figures 2 and 4, and the frames are so disposed that the channels face each other. The corners *b*¹ of the lower frame are of solid cross section as shown in Figure 3, and provided with projecting pins *c*. On the said pins *c* are arranged coiled springs *c*¹ capable of bearing against the corners of upper frame *a* which is secured at its corners to such pins *c* by washers *c*² and attached to the ends thereof of the pins by riveting over the ends or by means of split pins. The corners of the upper frame *a*

are recessed as at *d* (Figures 1 and 3) on the outer side in order that the ends of the pins *c* and the washers *c*² thereon may be disposed below the general plane of the outside surface of the upper frame *a*. The channels in the side bars of the upper frame increase in depth towards the centre of the length thereof as shown at *e* in Figure 3, and are fitted with the spring plates *f* which extend lengthwise of each side bar and have their ends engaged in apertures *f*¹ adjacent to the ends of the side bars and the corners of the upper frame. The lower frame *b* is provided with integral upstanding projections *g* which engage with recesses *h* in the upper frame *a* and have attached to their ends the outer ends *j* of the movable member *j*¹. Adjacent to the outer ends *j* are provided the cranked portions *j*² which are adapted in one position, such as is shown in the right hand half of Figure 4, when the movable member is in the position shown in Figures 1, 2 and 3, to bear on the spring plates *f* and hold the upper and lower frames *a* and *b* in the closed condition bearing on the racket disposed in the press. The springs permit rackets of varying thickness to be placed in the press and the movable member to be moved to the same extent in each case, that is from a position in which the loop handle portion *j*³ bears against the projection *k* to the position shown in Figure 1 in which the loop handle portion *j*³ bears against the projection *k*¹. Where the movable member is in the opposite position to that shown in Figure 1, the cranked portions *j*² are in the unclamped position shown at the left hand end of Figure 4. The outer ends *j* of the member *j* are rotatably mounted in upstanding projection *g*, while the latter operating in the recesses prevent relative lateral movement of the upper and lower frames. The spring plates *f* serve to equalize the pressure throughout the press, while the coiled springs *c*¹ hold the frames *a* and *b* apart when the movable member *j* is in the non-clamping position, and facilitate the introduction into or removal from the press of a racquet.

The alternative construction shown in Figures 5 and 6, comprises a closed upper frame *a*¹ and a closed lower frame *b*¹ connected at the corners by pins *c*⁴ fitted with coiled springs *c*⁵ for holding the frames apart as in the construction previously described. The pins *c*⁴ may be secured as shown in the lower part of Figure 6, to the lower frame *b*¹ and fitted at their outer ends in the manner already described with washers *c*⁶, for securing the upper frame thereto and at the same time permitting it to move on the pins *c*⁴ in opposition to the springs *c*⁵ thereon or the pins may be of telescopic construction as shown in the upper part of Figure 6, the pin portion *c*⁷ being secured

to the upper frame *a*¹ and the sleeve portion *c*⁸ to the lower frame *b*¹. In lieu of the sleeve there may be provided in the lower frame apertures for receiving the terminal ends of the pin portions. The side frames may be made of plain wood or sheet metal or of laminated wood with or without sheets of metal included therewith. The frames are provided with extensions *l* and *l*¹ for protecting the parts of a racket extending beyond the upper and lower edges of the usual form of press such as is shown in Figure 1. The lower frame *b*¹ is fitted with upstanding projections *g*¹ which engage with recesses *h*¹ in the upper frame *a*¹ while in the ends of the projections *g*¹ extending above the level of the upper frame is rotatably mounted a rod *j*⁴ provided with cranked portions *j*⁵ capable of engaging with the spring plates *f*² arranged on the upper surface of the upper frame *a*¹ and engaging at their ends with straps *f*³ secured to the frames *a*¹. To prevent excessive longitudinal movement of the spring plates *f*², the centre portions *f*⁴ thereof are recessed and receive the cranked portions *j*⁵ of the rod *j*⁴. The latter is adapted to be rotated by a lever *j*⁶ which may be provided on one or both ends thereof, or by a winged plate *j*⁷, either of which serve the same purpose as the lever *j*¹ in Figure 1.

In the arrangement shown in Figure 7, the clamping and unclamping of the press is effected by separate cranked portions *j*⁸ one of which is provided near each side margin of the upper frame *a*¹. Each cranked portion *j*⁸ forms a part of its respective rod *j*⁹ which is rotatably mounted at one end in the upper part of the upstanding projection *g*² attached to the lower frame *b*¹, and at the other end is similarly mounted in the overhanging portion *g*³ of the projection *g*². Each rod *j*⁹ is fitted with a winged plate *j*¹⁰ for rotating it and the cranked portion *j*⁸ for increasing or decreasing the pressure of the spring plate *f*².

The alternative construction shown in Figure 8 comprises a member *m* pivotally mounted on each upstanding projection *g*² and adapted to be operated by a lever *m*¹ for clamping and unclamping a racket between the upper and lower frames *a*¹ and *b*¹ through the spring plate *f*². Each side of the press is fitted with this form of means for operating the frames and the two levers thus required may be independently operated or may be connected by a link for operating the same collectively.

What I claim and desire to secure by Letters Patent of the United States is:

1. A racket press comprising, in combination, a pair of superposed frames, springs acting to separate said frames so that a racket may be positioned between them, and a rocking member mounted in bearings on

one of said frames and provided with a plurality of cam means, spaced longitudinally of said member and positioned adjacent opposite edges of the frame, adapted to simultaneously act to effect movement of the frames in opposition to the springs.

2. A racket press comprising, in combination, a pair of superposed frames, springs acting to separate said frames so that a racket may be positioned between them, two elongated yielding plates on one frame, in substantial parallelism with opposite edges of the frame, and a rocking member extending transversely across said frame and plates

15 and provided with cam means contacting with each of said plates, whereby as said member is rocked the frames will be forced toward each other in opposition to the intermediate springs.

20 3. A racket press comprising, in combination, a pair of superposed frames, each including two members adapted to extend lengthwise of the sides of a racket frame and cross bars connecting said members, 25 springs acting to separate said press frames so that a racket may be positioned between them, and a rocking member having coaxial oppositely directed arms engaging bearings on one of the press frames and each provided with cam means adapted to effect relative movement between the press frames in opposition to the springs as said member is rocked in its bearings.

4. A racket press comprising, in combination, a pair of superposed frames, each including two members adapted to extend lengthwise of the sides of a racket frame and cross bars connecting said members, springs acting to separate said press frames so that a racket may be positioned between them, two elongated yielding plates extending lengthwise of the side members of one of the press frames, a rocking member having coaxial oppositely directed arms engaging bearings on the other press frame and extending across said plates, each of said arms being offset in alignment with said plates, whereby the press frames will be moved in opposition to the springs as said member is rocked in its bearings.

SPENSER FLOWER.
